INVENTOR

ALFRED K. GEORGE

BY

HONORA S. SMITH,
2/15 ATTORNEY

UNITED STATES PATENT OFFICE.

ALFRED K. GEORGE, OF DAYTON, OHIO, ASSIGNOR OF ONE-HALF TO SIDNEY V. BURROWS, OF DAYTON, OHIO.

GRAPEFRUIT-SHIELD.

1,372,224.

Specification of Letters Patent. Patented Mar. 22, 1921.

Application filed November 22, 1920. Serial No. 425,724.

To all whom it may concern:

Be it known that I, ALFRED K. GEORGE, a citizen of the United States, residing at Dayton, in the county of Montgomery and State 5 of Ohio, have invented certain new and useful Improvements in Grapefruit-Shields, of which the following is a specification.

The principal object of my invention is to provide an adjustable shield that may 10 be readily applied to the top of a half or semi-spherical portion of a grape-fruit or an orange, to prevent the juice from flying into the face, or upon the clothing, of a person when he or she forces a spoon into it.

15 In the accompanying drawings, Figure 1 is a top plan view of my improved grapefruit shield. Fig. 2 is a side elevational view of the latter. And Fig. 3 is a bottom plan view of the same.

20 Throughout the specification and drawings, similar reference characters denote corresponding parts.

25 Referring to the accompanying drawings, the numerals 1, 2 and 3 respectively designate three sections of a metallic band or ring that is adapted to surround the semi-spherical portion of a grape-fruit or orange below its top marginal edge. Each section 30 of the band is turned over at its top, to rest upon the top marginal edge of said grape-fruit or orange portion.

The sections 1, 2 and 3 of the band are 35 adjustably secured together as follows. In one end of the turned-over portion of each section of the band, there is provided a slot 4 through which projects the shank of a flat-headed stud 5, on whose inner end there is 40 fixedly secured a collar 6 larger than said slot. The studs 5 have a longitudinal movement through the slots 4 to adjust the size of the band to that of the grape-fruit portion to which it is to be applied. Laterally 45 projecting teeth 7 are formed on the lower edge of the band, to penetrate the skin or shell of the grape-fruit a sufficient distance to hold the band firmly theron. (See Fig. 3.)

50 Suitably secured to the inner surface of the section 1 of the band, is an inwardly and upwardly projecting rib 8. To the inner end of the latter there is loosely secured, by

means of a pivot 9, a preferably fan-shaped shield 10, which has a horizontal rotary movement over the top of the semi-spherical portion of the grape-fruit. One radial edge 55 of said shield is turned up at its middle to form a canopy portion 11 under which a spoon is adapted to be forced into the juicy portion of the grape-fruit or orange to which 60 the band is applied.

When the spoon enters the grape-fruit or orange under the shield 10, the latter will prevent any of the juice from squirting into the face of the person eating it. Now when 65 the pulp is taken from the cavity portion of the fruit under the shield, the latter may be readily moved over the next cavity to shield the eater from any juice that may be forced upwardly from it, this operation being 70 repeated until all of the pulp is removed from the fruit.

The device may be constructed of any suitable material, and the band may be made up of any number of sections desired. 75 The shield 10 may also be formed in any suitable shape, and is secured to the rib 8 in such a manner that it may be rotated freely to any desired position when touched by a spoon.

80 Having described my invention, I claim:

1. In a device of the type described, the combination with an element adapted to be applied to the top of a portion of a grape-fruit or orange, and a shield adjustably secured to said element for movement over the top of said grape-fruit or orange portion, for the purpose specified. 85

2. A device of the type described for application to the top of a semi-spherical portion of a grape fruit, consisting of an annular element adapted to surround the top marginal edge part of said grape-fruit portion, a radial member secured to said annular element, over the top of said grape-fruit portion, and a shield pivotally secured to said radial member for a rotary movement in a horizontal plane over the top of said grape-fruit portion, for the purpose specified. 95

3. A device of the type described for application to the top of a semi-spherical portion of a grape-fruit, consisting of an ex- 100

pansible, sectional band adapted to be applied to the top marginal edge part of said grape-fruit portion, teeth on said band adapted to engage the skin of said grape-fruit portion, a radial rib secured to said band for projection over the top of said grape-fruit portion, and a fan-shaped shield pivotally secured to the inner end of said

rib for a rotary movement in a horizontal plane over the top of said grape-fruit portion, for the purpose specified. 10

In testimony whereof I have hereunto set my hand this 19th day of November, 1920.

ALFRED K. GEORGE.

Witness:

HOWARD S. SMITH.
